UNITED STATES PATENT OFFICE.

SAMUEL H. HELLER, OF LANCASTER, PENNSYLVANIA, ASSIGNOR OF ONE-HALF TO
ALFRED H. WORREST, OF LANCASTER, PENNSYLVANIA.

BLOTTER ATTACHMENT FOR FOUNTAIN-PENS.

1,174,415.

Specification of Letters Patent. Patented Mar. 7, 1916.

Application filed May 11, 1914. Serial No. 837,733.

To all whom it may concern:

Be it known that I, SAMUEL H. HELLER, of Lancaster, in the county of Lancaster and State of Pennsylvania, have invented 5 certain new and useful Improvements in Blotter Attachments for Fountain-Pens; and I do hereby declare the following to be a full, clear, and exact description of the invention, such as will enable others skilled 10 in the art to which it appertains to make and use the same.

My invention relates to an improvement in blotter attachment for fountain pens, and it consists of a sleeve or ferrule adapted to 15 be secured to a fountain pen, and a plug of absorbent material slidably mounted in said sleeve and adapted to project therefrom at one end.

In the accompanying drawings,—Figure 20 1 is a view of a pen showing my improvement applied thereto. Fig. 2 is a view of the attachment removed. Fig. 3 is a view in section of the attachment, and Figs. 4, 5 and 6 are views of modifications.

25 1 represents the cap of a fountain pen, which is of the well known construction, and 2 is a thin metal sleeve or ferrule open at both ends, and constructed to closely fit over the closed end of the cap. This sleeve 30 is preferably slit at one end, as at 3, so as to permit it to yield or give, and be forced onto the end of the cap and be held thereon by frictional contact against the possibility of accidental displacement or movement.

35 Located within the sleeve is a plug 4 of ink absorbing material, preferably made of blotting paper. This plug fits closely within the sleeve and is preferably held therein by frictional contact, and can be forced 40 lengthwise so as to cause it to project at the outer end. This plug is preferably made of disks of blotting paper lightly cemented together so that the exposed disk may be readily detached, or if it be made in an integral 45 mass of blotting paper, plaster of Paris or other ink absorbing material, the projecting ink saturated end may be severed with a knife and a new surface exposed by simply forcing the plug lengthwise 50 in the sleeve.

The sleeve 2 is preferably made of thin metal, but it may be rubber or other material and colored to conform to the pen, and as it is attached to the cap of the pen, it is always accessible for use, when the ordinary 55 blotting pads are not at hand or readily obtainable.

Instead of employing a sleeve to be secured to the cap of the pen as above described, the cap 1^a of the pen may be in 60 the form of a sleeve open at both ends as shown in Fig. 4, and carry the blotting pad therein, and when so constructed the pad is in a position, when the cap is covering the pen, to absorb any ink that may leak from 65 the pen, and if desired the end of the cap carrying the absorbent pad, may be provided with a cap or cover 5 as shown in Fig. 5 or a screw cap as at 5^a in Fig. 6 adapted to protect the blotting pad when the latter 70 is not in use.

The blotting pad may be pushed from the end of the cap or the sleeve in the cap, by simply pushing the cap farther down on the body of the pen, or by pushing the sleeve 75 down on the cap, so that the end of the body of the pen or the cap acts as a pusher to force the pad outwardly or it may be done by a screw motion of the cap or sleeve.

It is evident that changes in the construction and arrangement of the several parts might be made without avoiding my invention and hence I would have it understood that I do not restrict myself to the particular construction and arrangement of parts 80 shown and described, but

Having fully described my invention what I claim as new and desire to secure by Letters-Patent, is:

1. A blotter cap for fountain pens consisting of a cylindrical sleeve open at its ends, a cylindrical pad of absorbent material mounted in one end of said sleeve and held therein by frictional contact, whereby it may be withdrawn and the exposed end 90 detached, the other end of said sleeve being open for attachment to the pen holder.

2. A blotter attachment for fountain pens consisting of a sleeve open at its ends and an absorbent plug composed of connected 100

disks of absorbent or blotting paper within the sleeve and held therein by frictional contact, the said plug being movable within the sleeve whereby one end thereof may be projected through the sleeve.

In testimony whereof, I have signed this

specification in the presence of two subscribing witnesses.

SAMUEL H. HELLER.
